UNITED STATES PATENT OFFICE.

HARRY W. JONES, OF CHICAGO, ILLINOIS, ASSIGNOR TO AMERICAN CAN COMPANY, OF NEW YORK, N. Y., A CORPORATION OF NEW JERSEY.

POURING-SPOUT CONTAINER VESSEL.

1,152,416.

Specification of Letters Patent.

Patented Sept. 7, 1915.

Application filed December 7, 1912. Serial No. 735,363.

To all whom it may concern:

Be it known that I, HARRY W. JONES, a citizen of the United States, residing in Chicago, in the county of Cook and State 5 of Illinois, have invented a new and useful Improvement in Pouring-Spout Container Vessels, of which the following is a specification.

This invention relates to improvements 10 in pouring spout container vessels.

An object of the invention is to provide a hinged pouring spout for a container vessel which is readily attachable to the vessel by merely pressing or snapping the spout 15 into position.

The invention furthermore consists in the improvements in the parts and devices and in the novel combinations of the parts and devices herein shown, described or claimed.

20 In many kinds of container vessels such as are used in vending salt, cereals, washing powders and similar substances, it is desirable to provide pouring spouts for the convenience of the user and to prevent waste 25 or spilling of the substances while the same are being poured from the vessel. As is well known, these vessels are generally manufactured at one place and shipped to the various factories for filling. Hitherto it has

30 been customary to apply the pouring spout permanently to the vessel at the factory where the vessels are made and it has been found that considerable difficulty and inconvenience is encountered at the factories 35 where the vessels are subsequently filled with their contents, and frequently the pouring spout is injured during the filling operation, thus destroying the value of the entire vessel. With my improvements, the vessel or

40 can is provided with a pouring opening and thus shipped to the factories where the same are to be filled, and after the cans have been filled the pouring spouts which are shipped separately, are then applied entirely from 45 the outside, without the use of any special tools or appliances, by merely pressing or snapping the same in position and the pouring spouts so attached will remain in permanent position.

50 By employing an attachable spout, as in the manner above indicated, it is obvious that the filling of the vessels can be accomplished more readily and quickly than has

hitherto been possible and that waste of vessels will be eliminated.

55 In the drawings forming a part of this specification, Figure 1 illustrates an end view of a vessel showing my improvements in connection therewith. Fig. 2 is a partial, longitudinal, sectional view taken on the line 2—2 of Fig. 1. Fig. 3 is a view of the interior of a part of the vessel showing the spout in closed position. Fig. 4 is an elevation of a portion of the end of the vessel showing the outline of the pouring opening 65 and Fig. 5 illustrates the blank from which the pouring spout is formed.

In the drawing the main or body part of the container vessel is designated by the reference 10, and as shown, is provided with 70 a cover or end closure 11, the latter being provided near the perimeter thereof with a pouring opening 12. The opening 12, as more clearly shown in Fig. 4, is of tapered 75 formation and at one edge thereof are provided two inwardly extending projections 13, 13, said projections being oppositely arranged and each provided with an undercut portion 14, which in combination with projections formed on the pouring spout, hereinafter described, serve as hinge members 80 for the pouring spout.

The pouring spout is formed from a blank 15 having the general outlines shown in Fig. 5, which as shown, is scored on the dotted 85 lines 16, thus dividing the blank into a center portion 17 and two end portions 18, the latter forming the side walls of the pouring spout, and the inner or central portion 17 corresponding in size and shape to the pouring opening 12 and adapted to close the same 90 when the pouring spout is attached to the vessel. Each portion 18 forming the side walls of the spout is provided with a stop 19 adapted to limit the outward movement of 95 the spout as the same is swung about its hinge connection. The central portion 17 of the pouring spout is provided with a pair of projections 20, each having an inner cam face 21 and an undercut portion 22, the cam 100 faces and undercut portions being oppositely arranged as clearly shown in Fig. 5. The distance between the projections 20 on the pouring spout is such that the same are adapted to pass outside of the projections 105 13 with a relatively heavy frictional engage-

ment. The pouring spout is attached by pressing the projections 20 past the corresponding projections 13, whereupon the cam faces 21 will ride against the undercut portions 14 until the undercut portions 22 pass by the projections 13, whereupon the undercut portions 22 and 14 will snap into engagement and slightly overlap, as shown more clearly in Fig. 3. In this way a permanent hinge connection is formed between the spout and the vessel by means of the inter-engaging projections 13 and 20. A projecting shelf or lip 23 is provided along one edge of the pouring opening 12, which limits the inward movement of the pouring spout, which, during shipment, may be held down in position by means of a sticker pasted over the pouring spout.

The pouring spout and vessel are preferably formed of stiff paper or other fibrous material, but it will be obvious that the principle of the invention may be employed with the pouring spout and vessel made of other material such as sheet metal.

25 I claim:—

1. An article of manufacture of the character described comprising, in combination: a container vessel provided with a pouring opening; a pouring spout having side wings 30 and attachable to the vessel from the outside; and coöperating hinge-forming members on the spout and the vessel so arranged that the spout may be permanently attached by pressing the same into position, said hinge-forming members being undercut and 35 interlocking and acting to hold the spout to a fixed hinge line on the vessel while permitting its hinge action; substantially as specified.

40 2. An article of manufacture of the character described comprising, in combination: a container vessel provided with a pouring opening and having hinge-forming portions on the edge of said opening; and a spout 45 having hinge-forming portions adapted to coöperate with the hinge-forming portions of the vessel, all of said hinge-forming portions being so arranged that the spout may be permanently attached from the outside 50 by pressing the hinge-forming members together, said hinge-forming members being undercut and interlocking and acting to hold the spout to a fixed hinge line on the vessel

while permitting its hinge action; substantially as specified.

55

3. An article of manufacture of the character described comprising, in combination: a container vessel provided with a pouring opening having hinge-forming projections along one edge of said opening; and a spout 60 having hinge-forming projections coöperating with the hinge-forming projections on the vessel, some of said projections having notches in which engage, and are retained against movement in the plane of the top of 65 the container, others of the projections after the spout has been snapped into place; substantially as specified.

4. An article of manufacture of the character described comprising, in combination: 70 a container vessel provided with a pouring opening at one end thereof and having a pair of oppositely arranged hinge-forming projections on one edge of the opening, said hinge-forming projections being provided 75 with undercut portions; and a pouring spout having hinge-forming projections adapted to coöperate with the hinge forming projections on the vessel, the projections on the pouring spout being also provided with undercut portions adapted to engage the undercut portions of the projections on the vessel and interlock therewith against movement in the plane of the top of the container and hold the spout to a fixed hinge line, the 80 interengaging hinge-forming projections being so arranged that the pouring spout may be attached by merely pressing the same into position from the outside of the vessel after the same has been filled; substantially as 85 specified.

5. An attachable pouring spout for containers comprising an elongated piece of fibrous material having arcuate end sections and scored intermediate said sections, said 95 piece of fibrous material being provided with integral hinge-forming projections 20, 20, each having a cam face 21, and an undercut 22 arranged to hold the spout to a fixed hinge line while permitting its hinge movement; substantially as specified.

100 H. W. JONES.
